UNITED STATES PATENT OFFICE.

HARRY A. STEEN, OF EDGEWOOD, AND ALEXANDER J. LOGUIN, OF WILKINSBURG, PENNSYLVANIA, ASSIGNORS TO WESTINGHOUSE ELECTRIC AND MANUFACTURING COMPANY, A CORPORATION OF PENNSYLVANIA.

ELECTRICAL CONTROLLER.

No. 923,597.

Specification of Letters Patent.

Patented June 1, 1909.

Application filed September 3, 1907. Serial No. 391,241.

To all whom it may concern:

Be it known that we, HARRY A. STEEN, a subject of the King of Norway, and ALEXANDER J. LOGUIN, a subject of the Czar of Russia, residents, respectively, of Edgewood and of Wilkinsburg, in the county of Allegheny and State of Pennsylvania, have invented a new and useful Improvement in Electric Controllers, of which the following is a specification.

Our invention relates to electrical controllers and similar devices, and particularly to means for limiting the movements thereof.

The object of our invention is to provide means for preventing movement of a controller past the initial or "off" position, or any other predetermined position, without at least bringing the operating handle to a stop at the said position.

20 Electrical controllers for railway motors, and for motors employed to operate industrial apparatus, are usually provided with means for accentuating the initial and running positions, such that the controller cannot normally remain in an intermediate position. Such means, however, do not usually accentuate the positions sufficiently to prevent accidental movement of the controller beyond a position at which it may be desired to stop, as, for instance, the initial or "off" position to which the controller must be returned when it is desired to stop the motor governed thereby.

35 The present invention provides a very simple and effective device for preventing continuous movement of a controller past the "off" or another predetermined position, all possibility of accidentally reversing a motor, or of effecting other undesired results, being thereby avoided.

Figure 1 of the accompanying drawing is a plan view of a portion of the top of a controller constructed in accordance with our invention, and Fig. 2 is a vertical, sectional view on the line II-II of Fig. 1.

45 Rigidly secured to the upper end of a shaft 1 that projects through a casing 2 for the operating parts of the controller, and by means of which the movable circuit controlling parts are operated, is an actuating crank arm 3 that carries a handle 4 at its outer free end. Extending through the handle 4 is a rod 5 that carries a latch 6 at its lower end and is provided with a head or button 7 at its upper

end, the rod being surrounded within the handle by a helical compression spring 8, by means of which it, and the pawl 6, are normally maintained in the position indicated. When the latch 6 occupies its normal position it engages one of a series of notches 10 with which the downwardly turned flange 9 of a dial plate 11 is provided, said dial plate bearing, upon its upper face, position-indicating numbers or characters 12, respectively disposed opposite the notches 10 in the flange 9.

Pivotedly mounted upon a trap bolt 13, that is screwed into the under side of the dial plate 11 is a dog 14 comprising two projections 15 and 16 having rounded inner and straight outer edges, and an intermediate recess 17. The projections 15 and 16 project into the path of movement of the latch 6 when it is maintained in its lowermost position, as shown in broken and dotted lines, and the recess 17 is provided for the reception of the latch when the arm 3 occupies the position shown in the drawing, which may be the initial or "off" position, or any other predetermined position.

Surrounding a sleeve 18 upon the dog 14 is a helical torsion spring 19 the extremities of which are crossed and disposed upon opposite sides of two lugs 20 and 21, respectively upon the dog and the under side of the dial plate, the arrangement being such that the dog may be moved in either direction from the position shown, and it will be returned thereto by the spring. The dog 14 is limited in its movements by means of stops or lugs 22 and 23 which are disposed at opposite sides thereof upon the lower face of the dial plate.

In order to move the controller from its initial position, it is first necessary to move the latch 6 from engagement with the notch 10 in which it rests by pressing the head 7 downwardly against the action of the spring 8, and to then move the arm 3 in the desired direction. When the latch 6 is lowered to the position shown in broken and dotted lines, it occupies the recess at 17 in the dog 14, and as the arm 3 is rotated the dog 14 is also rotated upon its pivot until the latch 6 becomes disengaged therefrom, whereupon it is returned automatically by the spring 19 to the position shown, the lugs or stops 22 and 23 being disposed sufficiently far

2 apart to permit of such movement of the dog. When the arm 3 is returned to the position shown, the latch 6 engages the straight, outer edge of the one or the other 5 of the projections 15 or 16 and moves the dog into engagement with the one or the other of the stops 22 and 23, whereupon further movement of the arm in the same direction is prevented unless and until the latch 6 is 10 permitted to return to the position shown in full lines by releasing the pressure upon the button 7. It is thus seen that the controller may not be moved through its initial or "off" position, or through another pre- 15 determined position, without releasing the pressure upon the button 7 and again applying pressure thereto, which operations, of course, require some hesitation in the movement of the handle and thus prevent too sudden reversal of the connections of a 20 motor or other device governed by the controller. Accidental movement of the controller beyond its initial or "off" position, with the resulting undesired reversal of the 25 motor connections, is also prevented by the means above set forth.

It will, of course, be understood that the invention may be employed in connection with other devices than electrical controllers, and that the structural details and arrangement of the parts may be varied within wide limits from what has been shown and described, without departing from its spirit.

35 We claim as our invention:

1. In a controller, the combination with a movable arm, a latch and means for actuating the same carried by the arm, and a position-determining member with which the 40 latch is adapted to engage, of a pivoted dog in the path of movement of the latch having projections adapted to engage the latch and an intermediate recess for the reception thereof, means for limiting the movements 45 of the dog, and means for normally maintaining the dog in an intermediate position.
2. In a controller, the combination with a

movable arm, a spring-actuated latch and a spring-overcoming means carried by the arm, and a position-determining member 50 with which the latch engages when spring-actuated, of a stop for arresting the arm at a predetermined point until the latch is successively actuated by the spring and in opposition thereto.

55 3. In a controller, the combination with an arm having a spring-sustained and manually depressed latch adapted to be moved in either direction from a predetermined position, of a pivoted stop adapted to be engaged by said latch, when depressed, to arrest and retain the arm in said predetermined position, until released and again depressed.

4. In a controller, the combination with a 65 movable arm, a latch and means for actuating the same carried by the arm, and position-determining member with which the latch is adapted to engage, of a pivoted dog at a predetermined position in the path of 70 movement of the latch whereby movement of the arm past the said predetermined position is prevented except by causing engagement of the latch with and subsequent disengagement thereof from the position-determining member.

75 5. In a controller, the combination with an operating arm having a manually actuated latch, of a position-determining member with which the latch is adapted to engage, when released, and a stop device in position to be engaged by the latch when the arm is rotated and serving to prevent further movement of the arm until the latch is released and again manually actuated.

80 85 In testimony whereof, we have hereunto subscribed our names this 26th day of August, 1907.

HARRY A. STEEN.
ALEXANDER J. LOGUIN.
